197,415

RULER FOR SMOCK STITCHING OR THE LIKE

Blanche C. Mello, 38 Coolidge Road, Lynn, Mass.

Filed June 19, 1963, Ser. No. 75,416

Term of patent 14 years

(Cl. D52—6)

FIG. 1

FIG. 2

FIG. 3

FIG. 4

FIG. 5

FIG. 6

FIG. 1 is a top plan view of the ruler for smock stitching showing my new design;

FIG. 2 is a bottom plan view thereof;

FIG. 3 is a front elevational view thereof;

FIG. 4 is a rear elevational view thereof;

FIG. 5 is a left side elevational view thereof; and

FIG. 6 is a right side elevational view thereof.

The essential features of my design reside in the full line showings on the drawings.

I claim:

The ornamental design for a ruler for smock stitching or the like, substantially as shown and described.
